Primary Examiner — Derrick Holland*Assistant Examiner* — Lauren Calve(74) *Attorney, Agent, or Firm* — Brinks Hofer Gilson & Lione(57) **CLAIM**

I claim the ornamental design for a weatherproof electrical outlet cover, as shown and described.

DESCRIPTION

FIG. 1 is a front perspective view of a weatherproof electrical outlet cover showing an exemplary embodiment of my new design;

FIG. 2 is a rear perspective view thereof;

FIG. 3 is a left side view thereof;

FIG. 4 is a right side view thereof;

FIG. 5 is a front view thereof;

FIG. 6 is a top view thereof;

FIG. 7 is a bottom view thereof;

FIG. 8 is a front perspective view of the weatherproof electrical outlet cover of FIG. 1 in an open configuration;

FIG. 9 is a rear perspective view thereof;

FIG. 10 is a left side view thereof; and,

FIG. 11 is a right side view thereof.
